UNITED STATES PATENT OFFICE.

ROBERT H. HEY, OF PHILADELPHIA, PENNSYLVANIA.

STRAINER FOR WATER AND OTHER FLUIDS.

SPECIFICATION forming part of Letters Patent No. 338,523, dated March 23, 1886.

Application filed December 28, 1885. Serial No. 186,867. (No model.)

To all whom it may concern:

Be it known that I, ROBERT H. HEY, a citizen of the United States, residing in the city and county of Philadelphia, State of Pennsylvania, have invented a new and useful Improvement 5 in Strainers for Water and other Fluids, which improvement is fully set forth in the following specification and accompanying drawings, in which—

10 Figure 1 represents a longitudinal section of a strainer embodying my invention in line x x , Fig. 2. Fig. 2 represents a longitudinal section thereof in line y y , Fig. 1. Fig. 3 represents a transverse section in line z z , Fig. 2.
15 Similar letters of reference indicate corresponding parts in the several figures.

My invention consists of a strainer for water and other fluids, in which provision is made for readily cleansing the same without stopping the flow of fluid through the device.

20 Referring to the drawings, A represents a shell, which is of cylindrical form, and open at both ends, and provided with inlet and outlet branches B B at the sides.

25 C represents a cylinder or strainer chamber, which is fitted within the shell A, and made longer than the same, the ends of said chamber being closed by heads D, which are held in position by yokes E, whose ends are formed with 30 hooks or inwardly-extending lugs F, which engage with flanges G on the chamber, the crowns of the yokes being tapped to receive screws G', which bear against the heads D, and when tightened clamp the latter firmly against the 35 ends of the chamber C, thus reliably closing the same. Within the chamber is a perforated diaphragm, H, and a division-plate, J, the diaphragm H extending the length of the chamber from one head to the other close against the 40 same, the division-plate separating the chamber into compartments K L, which are not in communication.

45 In opposite sides of the wall of the chamber C, and on opposite sides of the plate J, are ports M N, which are so disposed that each pair of ports may be placed in communication with the branches B B of the shell A by moving the chamber C.

50 Connected with the flanges of the chamber C is a rack-bar, P, with which meshes a pinion, Q, the axis of the latter having bearings R, secured to the shell A. One of the branches is

connected with a supply-pipe, and the other with a pipe leading to the place of service.

According to the position of parts shown in 55 the drawings, referring more particularly to Fig. 2, the fluid first enters one side of the compartment L and passes through the diaphragm thereof, reaching the opposite side of the compartment in strained condition, and so 60 escapes through the discharge branch. Should the diaphragm or the receiving side of the compartment be clogged with sticks, leaves, dirt, &c., the same may be cleansed as follows: The pinion Q is operated by its handleS, 65 whereby the chamber C is shifted, and the ports N N are placed in communication with the branches B, and thus the fluid flows into the compartment K, where it is strained, and whence it escapes, the operation being accomplished without stopping the flow or supply of fluid to the strainer. The head of the compartment L is now removed, and the said compartment is accessible, whereby the matters 70 therein may be removed, the plate J, as is evident, preventing the fluid which flows through the diaphragm H from entering said compartment L. When the compartment K or its diaphragm becomes clogged or filled with improper substances, the head of the compartment L being previously restored the chamber 75 C is again shifted, so the ports M are again in communication with the branches B B. The head of the compartment K is now removed, and the interior of said compartment and its 80 diaphragm are accessible.

85 For convenience of cleansing the parts the diaphragm is made in sections, each section being separate from the divisional plate, so as to be readily displaced when the proper head 90 is removed.

Having thus described my invention, what I claim as new, and desire to secure by Letters Patent, is—

1. A strainer having the outer shell, A, with 95 branches B B on opposite sides, and the shifting-cylinder C, having ports M M and N N, substantially as described.

2. In a strainer, the shifting-cylinder C, provided with ports M M and N N, division-plate J, and diaphragm H, in combination with the outer shell, A, having both an inlet and outlet port, substantially as described.

3. A strainer having inlet and outlet open-

ings, and a shifting straining-chamber formed in divisions, each provided with ports which may be placed in communication with said openings and permit the straining of fluid without stopping the flow of the same while shifting the straining-chamber, substantially as described.

4. A strainer-chamber formed in sections separate from each other, each provided with ports, and an exterior shell with inlet and outlet openings, said chambers having detachable heads and made movable within said shell, substantially as described.

5. In a strainer, an inner shifting-cylinder having two compartments separated by a solid division-plate, each compartment being provided with a perforated diaphragm, and having an inlet and an outlet port and detachable heads, the said cylinder having means for shifting said cylinder in relation to the outer shell, substantially as and for the purpose set forth.

ROBERT H. HEY.
